UNITED STATES PATENT OFFICE.

JOSEPH CROSSLEY, OF TRENTON, NEW JERSEY.

CONTINUOUS MIXING-MILL.

1,231,499.

Specification of Letters Patent. Patented June 26, 1917.

Application filed February 5, 1917. Serial No. 146,688.

To all whom it may concern:

Be it known that I, JOSEPH CROSSLEY, a citizen of the United States, residing at Trenton, in the county of Mercer and State 5 of New Jersey, have invented certain new and useful Improvements in Continuous Mixing-Mills, of which the following is a specification.

My invention relates to the potters' art, 10 has especial reference to mills for mixing the material used for making pottery vessels, such as crucibles and the like, has for its object the reduction in cost and saving in time in preparing the material for the 15 molds.

The invention consists in certain improvements, which will be hereinafter fully disclosed and particularly pointed out in the specification and the claims.

20 The prevailing practice of preparing the material or composition of materials for the manufacture of crucibles comprises placing the pulverized clay, graphite and other ingredients in layers one upon the 25 other alternately in vats, and adding thereto the required amount of water, from 18 to 20 per cent. and allowing the water to soak through and thoroughly permeate the mass, and requires a number of hours to effect a 30 thorough soaking or wetting.

The soaked material is then cut out of the vats in thin vertical layers and put in a mixing mill, where it is agitated and discharged upon a floor and shoveled back into 35 the mill by manual labor, requiring two men to do the work.

This operation is repeated until the ingredients are properly mixed, and requires from one half to one hour of time.

40 The batch is then shoveled into a finishing mill, where it is treated from thirty to forty minutes, and requires the labor of two men to supply the mill.

In contradistinction to the foregoing practice, it is my purpose to put the pulverized composition properly moistened in a mixing mill in which it is agitated for a predetermined length of time, and transferring the batch from the lower end or bottom of the 50 chamber of the mill automatically to the upper end thereof. This operation is repeated until the batch has been thoroughly mixed, when it is transferred to a finishing mill, where it is prepared for use in molds.

55 During this operation a like mixing mill may be brought into use, and while the batch

in one mill is being discharged into the finishing mill, the batch in the other mill is undergoing a like agitation or mixing and transference from the lower to the upper 60 end repeatedly so that by the time the batch in one mill is discharged into the finishing mill, the batch in the other mill will be ready to be discharged into the finishing mill, while the discharged mill will be refilled 65 with a fresh batch of material.

I also propose to dispense with the soaking vats, by charging the pulverized ingredients into a stationary receptacle, such as a cylinder provided with revoluble agitators 70 or mixing blades, by which the ingredients are mixed preparatory to being treated in the mills, and in which operation, they become secondary mills or mixers.

The batch or charge in the primary mixers 75 may be mixed dry, or water may be supplied thereto while it is being mixed, or the batch may be moistened by supplying water thereto while it is being transferred from the primary mixer to the secondary 80 mixer.

The discharge of the material from the primary and the secondary mixers is controlled by suitable gates or valves operated by an attendant.

In the accompanying drawings, which 85 form part of this specification:—

Figure 1 is a front elevation of a machine embodying my invention.

Fig. 2 is a rear elevation of the same with 90 parts broken away to show interior construction.

Fig. 3 is a side elevation of the same.

Fig. 4 is a top plan view with the primary mixer removed, and

Fig. 5 is a detail section of the transferring device, on an enlarged scale.

Reference being had to the drawings and the designating characters thereon, the numeral 1 indicates the primary mixers, in 100 which the batch receives its initial treatment, and each consists of a fixed or stationary cylinder provided with a revoluble horizontal shaft 2 supported in pedestals or bearings 3, 3, and on the shaft 2 are secured 105 radially extending agitating arms or beaters 4 of well known construction, the hubs of which are properly secured to said shaft in the usual manner. Each cylinder is provided with a charging door 5 and a discharging door 6, and a pipe 7 extending longitudinally through the cylinder, slotted or 110

perforated at 7' to distribute water evenly to the batch of material to be treated, the supply of which water is regulated by a valve 8.

5 The batch may be mixed dry in the primary mixers, or it may be supplied with a part, or all of the water required, or more water may be supplied thereto in its passage from said mixers through a funnel 9, by 10 a like perforated or slotted pipe 10, controlled by a valve 11.

12 indicates the mixing mill of which there may be two and become secondary mixers in the operation of the continuous 15 mixing of a batch of material. These mills are exact duplicates, but will be designated as 12 and 12^a for the purpose of describing their relation and consecutive operation. Each mill comprises a vertical mixing chamber, 20 cylindrical in form, and is provided with a centrally arranged vertical shaft 13 extending through the bottom of the mixing chamber and on which shafts, are secured a reversely curved arm or scraper 14, 25 for pushing the material out of the chamber, and radial agitating arms 15 extending from hubs 16 which are properly secured to said shaft 13. On opposite sides of the transverse center of the mixing chambers are 30 openings 17 controlled by gates 18 for the discharge of the material into the cylinder 19; and openings 20 controlled by gates 21 for discharging the material into the finishing mill 22.

35 The gates 18 and 21 are operated by a rack 23 and pinion 24 on shaft 25 provided with hand-wheel 26, or in any preferred manner.

The cylinder 19 may be designated a transferring medium which is properly supported 40 and at its lower end communicates with the lower end of the mixing mill 12, or with it and the mill 12^a, when the two mills are used, through suitable openings registering with the openings 17 and controlled 45 respectively by the gates 18. The cylinder 19 is provided with a centrally arranged vertical revolute shaft 28, on which is a worm conveyer 29 for agitating and raising or elevating the material or batch as it proceeds 50 from the chamber or chambers of the secondary mixing mill or mills 12 and 12^a when forced out by the scraper 14.

On the upper end of the cylinder 19 is an axially movable turret or spout 30 controlled by a rack 31 and pinion 32 operated by shaft 31' and wheel 32' for directing the discharge of material into the mills 12 or 12^a, and on the upper end of the shaft 28 is a 55 scraper 33 operating in the turret 30, for cutting off the ascending material in layers, and pushing it out of the turret or spout into the upper end of the mill in which it is to be further treated.

The finishing mill 22 may be of any 60 proved form of construction as shown in my

Patent No. 473,497, bearing date of April 26th, 1892, and receives the material from the mill or mills 12, 12^a as it is discharged through the openings 20 controlled by gates 21, and is discharged through nozzle 22.

70 34 indicates a motor of any preferred form and from which power is transmitted through shaft 35 having a pinion 36 which meshes with master wheel 37 on shaft 38 on which are miter gear wheels 39 engaging wheel 40 on shaft 41 having a pinion 42 engaging wheel 43 on shafts 13 of the secondary mixers 12 and 12^a.

75 At the opposite end of shaft 38 are secured sprocket wheels 44 and 45, the former engaged by chain 46 which engages sprocket wheel 47 on shaft 48 having miter gear 49 engaging gear 50 on agitating shaft 51 in the finishing mill 22.

80 Sprocket wheel 45 carries a chain 52, engaging sprocket wheel 53 on shaft 54, on which is a beveled or miter gear wheel 55 engaging gear 56 on horizontal shaft 57 for expelling the contents of the finishing mill 22.

85 On one of the shafts 13 is secured a sprocket wheel 58 provided with chain 59, engaging sprocket wheel 60 on shaft 28 for operating the conveyer 29 and scraper 33.

90 Gates 6 controlling the discharge of the primary mixers 1 are operated by rack 61 engaged by pinions 62 operated by hand wheel 63.

95 Having thus fully described my invention, what I claim is—

100 1. A device for treating pulverized matter, comprising a plurality of mills each having a revolute agitator therein and an exit in the wall of each mill at its lower end, and a member external thereto and communicating at its lower end with said mixing mills through said exits and provided with an agitator and conveyer.

105 2. A device for treating pulverized matter, comprising a primary mixer, means for moistening said pulverized matter while in transit, a secondary mixing mill having a revolute agitator therein and an exit in its wall at the lower end, and a member external thereto and communicating at its lower end with said mixing mill through said exit, and provided with an agitator and raising conveyer.

110 3. A device for treating pulverized matter, comprising a mixing mill having a plurality of exits or discharge passages in its wall at the lower end, means for forcibly ejecting the material in said mill through said exits, a member external thereto and communicating at its lower end with the mixing mill through one of said exits, and provided with a revolute conveyer, and an additional mill supplied from the mixing mill through the other exit.

115 4. In a device of the class described, a

member comprising a cylinder having an inlet passage in the wall thereof at its lower end, means for controlling said passage, and an axially movable spout on the upper end 5 of the cylinder, with a revoluble scraper therein.

5. A plurality of mixing mills, each provided with exits or discharge passages in their walls and at their lower ends, a device 10 for transferring the contents of said mills and communicating therewith at its lower

end through said passages, and means for controlling the passages and placing the transferring device in communication through said exits with the mixing mills.

15

In testimony whereof I affix my signature in the presence of two witnesses.

JOSEPH CROSSLEY.
